US0D1060696S

(12) **United States Design Patent** (10) **Patent No.:** **US D1,060,696 S**
(45) **Date of Patent:** **** Feb. 4, 2025**

(54) **PHOTOTHERAPY DEVICE**

- (71) Applicant: **Basolite Ltd**, Spennymoor (GB)
(72) Inventor: **Gordon Dougal**, Spennymoor (GB)
(73) Assignee: **Basolite Ltd**, Spennymore (GB)
(**) Term: **15 Years**
(21) Appl. No.: **29/932,514**
(22) Filed: **Mar. 14, 2024**

Related U.S. Application Data

- (62) Division of application No. 35/516,434, filed on Dec. 8, 2022 (U.S. filing date under 35 U.S.C. 384), and having an international filing date of Dec. 8, 2022.

CLAIM

The ornamental design for a phototherapy device as shown and described.

DESCRIPTION

FIG. 1 is a perspective view on rear of the phototherapy device;

FIG. 2 is a perspective view on front of the phototherapy device;

FIG. 3 is a rear elevational view of the phototherapy device;

FIG. 4 is a front elevational view of the phototherapy device;

FIG. 5 is a left side elevational view of the phototherapy device;

FIG. 6 is a right side elevational view of the phototherapy device;

FIG. 7 is a top plan view of the phototherapy device; and,

FIG. 8 is a bottom plan view of the phototherapy device.

The broken lines shown in the drawings depict of environmental structure and form no part of the claimed design.
